Primary Examiner — Messina L Smith*Assistant Examiner* — Elizabeth Borsetti*(74) Attorney, Agent, or Firm* — S.J. Intellectual Property LTD.(57) **CLAIM**

The ornamental design for a wig grip band, as shown and described.

DESCRIPTION

FIG. 1 is a front, right and bottom perspective view of a wig grip band, showing my new design;

FIG. 2 is a rear, left and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view of the wig grip band, shown in an environment of use.

The broken lines in the drawings depict portions of the wig grip band that form no part of the claimed design. The additional broken lines showing of a humanoid figure in FIG. 9 depict environmental structure that form no part of the claimed design.
